UNITED STATES PATENT OFFICE.

ALFRED MATHIS, OF NORTH BERGEN, NEW JERSEY, ASSIGNOR TO M. M. COMBINATION SHADES AND CURTAINS HANGER MANUFACTURING COMPANY, OF NORTH BERGEN TOWNSHIP, NEW JERSEY, A COMPANY COMPOSED OF SAID ALFRED MATHIS.

COMBINATION BRACKET.

Application filed July 12, 1922. Serial No. 574,431.

To all whom it may concern:

Be it known that I, ALFRED MATHIS, a citizen of the United States, residing at North Bergen, in the county of Hudson and State of New Jersey, have invented new and useful Improvements in Combination Brackets, of which the following is a specification.

This invention relates to combination brackets.

More particularly the invention relates to combination brackets such as are used for supporting curtain pole, drapery rod and rolled shade.

Some of the objects of the present invention are:—To produce comparatively simple brackets of the character mentioned, to reduce the number of parts; to employ a plurality of brackets of the present type on the frame of a window, which are capable of being adjusted to accommodate a curtain, drapery and window shade regardless of the widths respectively of the curtain, drapery and window shade within certain limits; and with these and other objects in view the invention resides in the particular construction and relative disposition of parts hereinafter fully described, and illustrated in the accompanying drawing, in which:—

Figure 1 is an elevation of the upper portion of a window structure with a pair of brackets of the present invention applied thereto ready for use to properly support a curtain, drapery and ordinary rolled window shade.

Figure 2 is a perspective view of one of the brackets attached.

Figure 3 is a sectional view taken on the line 3—3 of Figure 1.

Figure 4 is a sectional view on the line 4—4 of Figure 1.

Referring more particularly to the several views of the drawing, and especially with reference to Figure 1, it will be apparent that use is made of a pair of brackets 10. The brackets are substantially identical in construction except in one respect and that will be pointed out hereinafter. Inasmuch as the brackets are substantially identical a description of one will suffice the other.

The bracket 10 comprises an attaching plate 11, a bracket member 12 and means

13 for temporarily holding the bracket member 12 in different positions of adjustment on the attaching plate 11. The attaching plate 11 may be of any outline and is provided with holes on the opposite ends thereof, for the reception of fastening elements such as screw 14 for effecting the attachment of the plate to the frame of the window structure 15. The bracket member 12 is formed preferably of a single piece of material to provide a part 16, part 17, and an intermediate part 18. The part 16 is bent forwardly and downwardly as at 19, then upwardly as at 20 and then bent into a semi-circular portion 21. Part 17 is disposed at a right angle with respect to the part 18 and the part 17 has a hole 22 therein. At this point, it is well to mention that the part 17 of the other bracket 10 has a notch instead of a hole 22. The means 13 comprises a member 23 and a set screw 24. The member 23 has a recess 25, a screw threaded hole 26, and holes in the opposite ends for the reception of screws which are employed for removably attaching the member 23 to the plate 11. The said screw 24 is adapted to be screwed into the hole 26. In the assemblage of the several elements the part 18 of the bracket member 12 is disposed in the recess 25 and is movable therein for the adjustment of the bracket member with respect to the attaching plate 11. The end of the set screw 24 may be screwed against the part 18 of the bracket member 12 to hold the latter temporarily in its adjusted position and this way the parts 17 of the brackets 10 may be set apart in the desired distance to accommodate the particular rolled window shade. A curtain pole may be positioned in the semi-circular portion 21 for the hanging of a curtain and a rod may be positioned behind the portions 20 to be supported by the junctures between the portions 19 and 20 for the hanging of a drapery. The parts 17 of course serve for the support of the ordinary shade roller; one part accommodating the squared end of the spring actuated shaft whereas the other part accommodates the pintle of the opposite end of the shade roller.

What is claimed as new is:—

A bracket comprising an attaching member, a bracket member formed of a single

piece of material and bent to provide spaced supporting parts connected by an intermediate part, one of said supporting parts being bent upwardly, downwardly and forwardly, thence upwardly to form the notch for the reception of a drapery rod, and thence forwardly to form a semi-circular portion for the reception of a curtain pole, the other supporting part being bent outwardly and provided with a slot for the reception of a shade roller, and means carried by the attaching plate for adjustably

supporting the bracket member between the supporting parts, said means including a plate removably mounted on said attaching member and having a passage therein for slidably receiving said intermediate part, and a set screw carried by said plate for clamping engagement with said intermediate part.
